UNITED STATES PATENT OFFICE.

WILLARD M. HIATT, OF WESTON, MISSOURI.

CAR-COUPING.

SPECIFICATION forming part of Letters Patent No. 237,016, dated January 25, 1881.

Application filed August 18, 1880. (No model.)

To all whom it may concern:

Be it known that I, WILLARD M. HIATT, of Weston, in the county of Platte and State of Missouri, have invented certain new and useful Improvements in Car-Couplings; and I do hereby declare that the following is a full, clear, and exact description of the invention, which will enable others skilled in the art to which it appertains to make and use the same, reference being had to the accompanying drawings, which form a part of this specification, and in which—

Figure 1 is a vertical longitudinal section of my improved car-coupling, and Fig. 2 is a horizontal section of the same, taken through line $\alpha\alpha$, Fig. 1.

Similar letters of reference indicate corresponding parts in both the figures.

This invention has relation to improvements in car-couplings of that class in which the operation of coupling is automatic, while the uncoupling operation does not require the attendant to go in between the cars where they closely approach each other; and it consists in the detailed construction and arrangement of the parts, substantially as hereinafter more fully set forth and claimed.

In the accompanying drawings, A indicates the draw-head, and B is the coupling-pin. A short distance up from its lower end it is shouldered, as shown at b, to aid in holding the link down in the draw-head. The pin is hung at c in a plate, d, which is also hung or pivoted in the draw-head upon a pin, f. To the upper side of the hinged or pivoted plate d is attached, by a staple, preferably, a ring, e', to afford a means of attachment for a chain or other suitable medium, connected to an elevated point on the car, to permit of the uncoupling of the cars without requiring the attendant to go in between the closely-approaching portions of the cars.

C is a gravitating lever or tongue, hung in the draw-head directly under the hinged or pivoted plate d upon a pin or bolt, e, with its rear end weighted eccentrically to its pivot, or so as to cause its tongue or forward end, C', to press against the pin and permit the latter to move rearwardly in the arc of a circle, and after being released to return to its former or normal vertical position. The under side of plate d is hollowed out to cause it to fit snugly the upper weighted end of the gravitating tongue or lever C C'.

To effect the operation of coupling, force the link D against the pin through the usual opening in the draw-head. This action of the link will swing the pin rearwardly and upward, and thus permit the link to pass under and beyond the pin. The gravitating lever or tongue will instantly return the pin to its normal position, swinging it back at its lower end in the slot or opening in the link, and thus effect the coupling. A slot, f', is made in the bottom of the draw-head to permit the pin to have the above-described swinging motion.

I claim as my improvement and desire to secure by Letters Patent of the United States—

In a draw-head for railway-cars, the combination, with the hinged and recessed plate d, and hinged pin B, shouldered at b, of the pivoted wedge-shaped tongue C C', bearing with its pointed end against the pin, and with its broad or weighted end against plate d, as shown and set forth.

In testimony that I claim the foregoing as my own I have hereto affixed my signature in presence of two witnesses.

WILLARD MILTON HIATT.
